DIVING BOARD

Myron P. Anthony, Newport Beach, Calif., assignor to Anthony Pools, Inc., South Gate, Calif., a corporation of Delaware

Filed June 6, 1962, Ser. No. 70,434

Term of patent 14 years

(Cl. D13—1)

FIGURE 1 is a perspective view of a diving board embodying my new design in which the configurations of the block and the associated handrail are the dominant features; and FIGURES 2, 3 and 4 are top, side elevational, and front elevational views, respectively, thereof.

The dominant features of my design reside in the portion shown in full lines. The fragmentary showing of the pool coping and the coil spring underlying the diving board, all appearing in broken lines, are for illustrative purposes only.

I claim:

The ornamental design for a diving board, as shown and described.
